LIGHTING FIXTURE HANGER

Gale F. Thomas, Inglewood, Calif., assignor to Smooth-Holman Company, Inglewood, Calif., a corporation of California

Application September 22, 1958, Serial No. 762,594

10 Claims. (Cl. 248—317)

This invention relates to lighting fixtures hung from a ceiling, or other overhead structures, and in particular to a fixture hanger including means for leveling and stabilizing the fixture against vibration or shock.

Lighting fixtures, especially the fluorescent type, present an installation problem when hung from a sloping or uneven ceiling, for example. The fixtures available are rigidly built to be hung from a horizontal surface and cannot be leveled or aligned without modifying by shortening or bending parts of the fixture at considerable inconvenience while installing the same. Furthermore some available fixtures are not suitably stabilized against vibration in that they are relatively free swinging and can build up large amplitudes of swing due to resonance because they do not offer increasing resistance to swinging as the angle of swing increases. Also, some available fixtures are so rigidly constructed that they do not suitably absorb shocks caused by the passage of heavy vehicles or by earthquakes. This may result in fracturing fragile parts of the fixture such as lenses, reflectors, lamps, etc.

Accordingly, it is an important object of my invention to provide a hanger for a lighting fixture which is free of all of the above-described disadvantages and defects.

Another object of my invention is to provide a hanger for a lighting fixture which includes means for rapidly and conveniently leveling and aligning the fixture even when hung from sloping or uneven structural surfaces.

A further object is to provide such a hanger which is stabilized against excessive swinging but also will absorb sudden strong vibrations and shock without injury to fragile parts of the fixture.

Additional objects will become apparent from the following description which is given primarily for reasons of illustration and not limitation.

Stated in general terms, the objects of my invention are attained by attaching the support bars of the fixture, such as the vertical support bars, to a resilient member, preferably a resilient torsion member, which, in turn is attached rigidly to the fixture structure proper. The torsion bar is made of resilient material, such as a spring steel, and is dimensioned and shaped relative to the fixture to absorb vibration and shock waves transmitted through the support bars. Also, the torsion bar is adapted to increase its stabilizing reaction as the action of the vibration or shock waves tends to increase the degree of sway or swing of the fixture. In addition, the frame of the fixture adjacent the torsion bar is provided with adjustment means adapted to bear on the torsion bar with controlled degree of force to conveniently level or align the fixture by slightly displacing the position of the fixture proper relative to the positions of the support bars.

A more detailed description of a specific embodiment of my invention is given below with reference to the attached drawings, wherein:

Fig. 1 is a partial isometric view of an assembly consisting of an end frame member or stabilizer containing

2

a torsion bar to which is attached a vertical support member;

Fig. 2 is a partial sectional elevational view taken along the line 2—2 of Fig. 1 and drawn to an enlarged scale;

Fig. 3 is a partial isometric view showing a torsion bar and a nut attached at the middle thereof;

Fig. 4 is a perspective view showing two fixture units combined in end-to-end relationship;

10 Fig. 5 is a partial plan view showing an end-to-end connection of two adjacent units combined as shown in Fig. 4; and

Fig. 6 is a vertical sectional view taken on line 6—6 of Fig. 5 showing the stabilizer mounted in a housing.

The torsion bar or strap member 10 preferably is made of stainless steel because this metal is suitably resilient, strong and durable. Other metals having similar properties can, of course, be used. The particular shape and dimensions of the torsion bar will depend, in each case,

20 upon the particular lighting fixture in which it is installed. In the embodiment shown in the drawings the torsion bar 10 is made of a flat strip of sheet metal. The strip is formed in a press, for example, to have raised end portions 11 and 12, a raised central or middle portion 13 and two depressed intermediate portions 14 and 15, respectively. The depressed portion 14 is formed between the raised end portion 11 and the raised middle portion 13 and the other depressed portion 15 is formed between the other raised end portion 12 and the raised

30 middle portion 13. A central hole 17 is cut through the middle portion 13 and a flat threaded pad or nut 18 is fastened to the under side of the middle portion by any suitable means, such as by spot welding, with an internally threaded hole 19 of the pad or nut aligned with the

35 hole 17, as best shown in Fig. 3. Circular recesses 21 and 22 are formed in depressed portions 14 and 15, respectively, equidistant from the center of hole 17.

As best shown in Fig. 2, the torsion bar 10 is fastened inside a horizontal base element or inverted channel-shaped stabilizer 23 having upper and lower surfaces as shown and with the raised middle portion 13 projecting freely through a square opening or hole 24 cut in the middle of the top 26 of the stabilizer. The hole 24 is made larger than the portion 13 to avoid touching of the edges of the hole by the torsion bar 10. Rivets 27

40 are shown passing through holes 28 in the stabilizer top 26 and holes 29 in the torsion bar raised end portions 11 and 12, respectively, for attaching the torsion bar 10 to the under side of the stabilizer top 26, but it will be

50 understood that the attachment can be made by any other suitable fastening means such as spot welding, brazing, bolts, screws, etc., as desired. Leveling screws 31 and 32 are threaded into internally threaded holes formed in the stabilizer top 26 so that the screws can be made to engage in the recesses 21 and 22, respectively, in the

55 top of torsion bar 10, as best shown in Fig. 2.

A vertical support or suspension tube is provided in the form of a threaded steel tubing stem 33 having a nut 34 (Fig. 2) threaded on the threaded end 36 thereof.

60 The threaded end 36 of the stem 33 is screwed into the internally threaded hole 19 of the pad or nut 18 the desired distance and a safety bushing or cap member 37 is tightly threaded onto the protruding threaded end of the tubing stem 33 to engage against the under side of pad 18. The nut 34 then is drawn tightly down onto the top of the exposed middle portion 13 of the torsion bar 10 to tightly secure the tubing stem 33 on the torsion bar.

65 The stabilizer channel 23 is then enclosed in a stabilizer housing 38 which can be made up of two vertical side channels 39 and 40, for example, or any suitable end cap construction to enclose the stabilizer therein. Each end

of the lighting fixture is provided with such an assembly of stabilizer 23, torsion bar 10, tubing stem 33 and stabilizer housing 38. The lamp housings 42 and 43 (Fig. 4) of the fixture are mounted in spaced parallel arrangement between two such end assemblies and are reinforced by a cross-member 44 fastened between the mid-portions of the lamp housings. The cross-member 44 also serves as the housing for the ballast.

A lighting fixture consisting of a single unit is suspended by two tubing stems 33 from a ceiling so that electrical connection is made through an electric outlet box, by means known in the art. Any departure of the plane of the fixture from the horizontal is rapidly and efficiently corrected by simply using a screw driver to turn one or both leveling screws 31 and 32 into the stabilizer top 26. The leveling screws 31 and 32 then are brought to bear against the top of torsion bar 10 in recesses 21 and 22, respectively, with different degrees of pressure on opposite sides of the axis of the tubing stem 33 in each of the two cases. The result of this action is to cause one side of the torsion bar 10 to be depressed more than the other side thereof, as shown by dotted lines in Fig. 2. This produces a transverse angle of tilt in the fixture to take care of any slope in the ceiling transversely to the lighting fixture. It also can be made to balance or level the largest degrees of unbalance such as may be caused by four heavy electrical feed wires in one of the stabilizer housings or one of the side channels. If one end of the fixture is at a lower level than the other end, this deviation from a horizontal plane readily can be corrected by turning one of the tubing stems farther into the pad or nut 18 and, if desired, partially unscrewing the tubing stem 33 at the other end of the fixture.

It will be seen that a lighting fixture hung in this manner will be permitted to sway or swing both longitudinally and transversely when caused to do so by vibration or shock waves transmitted thereto through tubing stems 33. The amplitude of such swinging will, however, be kept relatively small because of the resilient reaction in the torsion bar 10. As the amplitude of the swings tends to increase, such as by resonance effects, the counteracting strains in the torsion bar act with increased force against the swings to prevent successive increases in amplitude. In this manner the energy of the vibration and shock waves is largely absorbed in the torsion bar and is not transmitted unabated to the lighting fixture proper. Fragile parts and components of the fixture are, therefore, effectively protected from breakage and other damage. Occupants of the rooms in which the lighting fixtures are mounted are correspondingly protected from injury and panic which may be initiated by falling parts of broken light fixtures during an emergency.

For continuous mounting of a plurality of fixtures in end-to-end relationship, as indicated in Fig. 4, the procedure is similar to that described above for a single fixture. One stabilizer 23 is used between two adjacent fixtures as best shown in Fig. 5. The adjacent fixtures are keyed into the stabilizer, as shown, and the resulting stabilizer and torsion bar assembly is housed inside a housing 38 consisting of two vertical channels 39 and 40 mounted on the stabilizer, as described above in connection with the description of a single fixture. The leveling operations also are the same as those described above for a single fixture installation, as are the operations of the torsion bars in absorbing the energy of shock and vibration waves and in protecting the lighting fixture from damage.

Although a specific embodiment of my invention has been described and illustrated above, it will be understood that other embodiments of the invention can be made by the incorporation of changes or modifications within the skill of the art and without departing from the spirit of the invention. I desire, therefore, to be afforded the full scope of the following claims.

I claim as my invention:

1. In a lighting fixture hanger, the combination of:

4
a horizontal base element, having an opening therein, and having upper and lower surfaces;

a member disposed adjacent to one of said surfaces in alignment with said opening,

said member being formed of resilient material,
said member having ends rigidly secured to said one of said surfaces, and

having a pair of intermediate portions therebetween on each side of said opening and spaced from said one of said surfaces, and

having a central portion aligned with said opening and connecting said intermediate portions and being bent into said opening; and connecting means for attaching a vertical support to said central portion of said member.

2. A device as set forth in claim 1, having adjustment means between the base element and the member for varying the spacing therebetween.

3. A device as set forth in claim 1, having adjustment means between the base element and each of the intermediate portions of the member for independently varying the spacing between each of the intermediate portions and the base element.

4. A device as set forth in claim 1, in which the connecting means includes a pad element rigidly secured to the central portion of the member and having a threaded opening therein adapted to receive a threaded vertical support.

5. A device as set forth in claim 1, in which the central portion of the member extends through the opening of the base member to provide a bearing surface spaced from the other of the surfaces of the base element.

6. A device as set forth in claim 1, in which the member is relatively thin and has a length substantially greater than its width.

7. In a lighting fixture hanger, the combination of:

a horizontal base element, having upper and lower surfaces, and having an opening therein;

a strap member disposed adjacent to said lower surface, said member being formed of resilient metal,
said member being relatively thin and having a length substantially greater than its width, and
having ends rigidly secured to said lower surface, and

having a pair of intermediate portions therebetween and spaced from said lower surface, and

having a central portion aligned with said opening and connecting said intermediate portions and bent upwardly through said opening to provide a bearing surface thereabove;

a pad element rigidly secured to said strap member aligned with said central portion thereof and having a threaded opening therein;

a vertical support having an externally threaded end threaded through said threaded opening;

a cap member threaded on the end of said support and engaging against one side of said pad element; and
a nut on the threaded portion of said support and engaging against said bearing surface.

8. A device as set forth in claim 1, in which a pair of threaded openings is formed in said base element on each side of the opening therein and aligned with the member, there being an adjustment screw threaded through each of said threaded openings to adjustably engage an intermediate portion of the member, the member being provided with a pair of recesses to receive the ends of said adjustment screws.

9. In a lighting fixture hanger, the combination of:

a horizontal base element having upper and lower surfaces;

an elongated member disposed adjacent to one of said surfaces,
said member being formed of a resilient material,
said member having a central portion adapted to be connected to the lower end of a vertical support,

said member having opposite ends rigidly secured to said one of said surfaces, and

having an intermediate portion on each side of said central portion which is spaced from said one of said surfaces;

connecting means associated with said central portion for attaching a vertical support to said member; and

adjustment means between said base element and said member for varying the spacing therebetween.

10. In a lighting fixture hanger, the combination of: 10

a horizontal base element, having an opening therein and having upper and lower surfaces;

an elongated strap member disposed adjacent to said lower surface in alignment with said opening,

said strap member being formed of resilient metal, 15

said strap member having opposite ends rigidly secured to said lower surface, and

having at least one intermediate portion between said ends and spaced from said lower surface;

connecting means associated with said strap member and adapted to attach a vertical support to said member so that said support extends through said opening; and

adjustment means between said base element and said strap member for varying the spacing therebetween.
